UNITED STATES PATENT OFFICE.

ROY P. WILLIAMS, OF PASADENA, CALIFORNIA, ASSIGNOR TO A. M. DRAKE, OF PASADENA, CALIFORNIA.

SPRAY-NOZZLE.

1,183,150.

Specification of Letters Patent.

Patented May 16, 1916.

Application filed June 22, 1915. Serial No. 35,527.

To all whom it may concern:

Be it known that I, ROY P. WILLIAMS, a citizen of the United States, residing at Pasadena, in the county of Los Angeles and State of California, have invented a new and useful Spray-Nozzle, of which the following is a specification.

My invention relates to spray nozzles.

In the practical utilization of water in connection with gardening, it is desirable to provide means whereby the water can be evenly distributed over considerable areas, and in which both the fineness of the spray and the area sprayed can be readily controlled.

The principal object of my invention is to provide such a spray nozzle. Sometimes such a spray nozzle may be used in connection with a line of flexible hose, one or more of these nozzles being connected into the hose and being moved from place to place as desired. At other times the spray nozzles are permanently located, being connected to underground systems of piping, so that it is simply necessary to turn the water pressure on when it is needed.

A further object of my invention is to provide a spray nozzle which may be used both with flexible hose and with underground systems of piping.

In such a spray nozzle there is some likelihood of dirt or waste matter accumulating in the inside of the nozzle, and a further object of my invention is to provide a spray nozzle in which the working parts may be readily removed through the top whenever it is necessary for the purpose of cleaning. It is further desirable in such a spray nozzle to provide means by which the nozzle can be adjusted, such means being preferably permanently secured in the nozzle itself, and it is a further object of my invention to provide means for this purpose.

Further objects and advantages will be made evident hereinafter, or will be evident to one skilled in the art upon an inspection of the accompanying drawing, and a perusal of the following specification.

In the form of my invention illustrated in the drawing; Figure 1 is an elevation of a hose nozzle adapted for use with a line of flexible hose, and provided with an integral adjusting stem, the larger part of the nozzle being shown in section for the purpose

of better illustrating the invention. Fig. 2 is a plan view of the hose nozzle shown in Fig. 1, the line x^1-x^1 representing the plane on which the section of Fig. 1 is taken. Fig. 3 is a section on the plane x^2-x^2 of Fig. 1. Fig. 4 is a section of the upper portion of an alternative form of my invention which is especially adapted for use in underground systems.

Broadly considered, my invention consists of a supporting member 11, a body member 12, a plug 13, and an adjusting means 14. The supporting member 11 may consist of a T having lower branches 21 and 22, and an upwardly extending branch 23, a cap 24 and a washer 25 being provided for closing the branch 21, the branch 22 having an inwardly extending thread 26 and a washer 27, the thread 26 being adapted to receive the end of a standard garden hose. In a similar manner the cap 24 may be removed and the interiorly threaded end of a garden hose may be secured thereon, so that a number of body members 11 may be secured in series if desired. Arms 28 are secured on the side of the supporting member 11 extending outwardly therefrom for the purpose of holding the upwardly extending branch 23 in a vertical position as the flexible hose is moved about. The body member 12 is secured by means of a thread 31 to the exterior of the branch 23, this body member having an interiorly threaded cavity 32 extending upwardly therethrough. A series of helical grooves 33 are cut in the walls of the cavity 32, these grooves being similarly inclined and tapering gradually in sectional area as they ascend. The grooves 33 terminate at a point 34 near the top of the body member 12. A cap 35 is threaded into the top of the cavity 32 being provided with small holes 36 for the reception of a spanner wrench, an outlet opening 37 being centrally formed therein.

The plug 13 is exteriorly threaded into the cavity 32 having a central cavity 41 formed therein, this cavity 41 terminating in a top 42 which completely closes the opening through the cavity 32, the grooves 33 extending into the walls of the body member outside the plug 13. A series of ports 43 are cut in the walls of the plug 13, these ports 43 having an opening approximately equal to the width of the lower ends 110

of the grooves 33. The walls between the ports 43 are sufficiently wide to completely cover the grooves 33 when the plug 13 is turned to the closed position.

The adjusting means illustrated at 14 consists of an upwardly extending stem 44 having a knurled head 45, this stem 44 extending upwardly through the outlet opening 37. A square head may be substituted for the knurled head 45 if desired, so that a wrench can be applied for the purpose of turning the plug 13. A standard pipe fitting may be substituted for the body member 12, this pipe fitting being secured in a line of pipe buried in the ground, the top of the body member 12 being also buried so that the top thereof is a little below the surface of the ground. When so used, the method of construction illustrated in Fig. 4 is preferable to the method illustrated in Fig. 1.

In Fig. 4 the adjusting means in the plug 13 consists of a projection 50 having a rectangular slot 51 cut therein. When it is desired to adjust the plug 13 in the body member 12 in the form shown in Fig. 4, it is necessary to insert a wrench or screw driver through the outlet opening 37, this wrench or screw driver engaging the slot 51 and allowing the plug 13 to be moved up or down.

The method of operation of the invention is as follows: Water being supplied to the interior of the body member 12, through the supporting member 11 shown, or through an equivalent pipe fitting, this water rises through the upwardly extending branch 23, passing into the lower portion of the cavity 32 and into the cavity 41 inside the plug 13. If the plug 13 is in the open position, the ports 32 register with the lower portion of the grooves 33 and water is supplied to the lower portion of these grooves. This water entering the grooves at a certain velocity, is rapidly accelerated due to the reduction in the sectional area of the grooves, and finally emerges at the point 34, just above the top of the plug 13, at a considerably increased velocity. As the grooves 33 are inclined, the water enters the space between the top of the plug 13 and the cap 35 in a tangential direction, setting up a rapidly whirling vortex of water between the top of the plug 13 and the cap 35. As water is added to this vortex through the grooves 33 it overflows through the outlet opening 37 and is thrown off spirally in all directions around the spray nozzle. By adjusting the plug 13 up and down in the cavity 32, the size of the port opening at 34 may be increased or diminished, and the velocity of the water entering the space above the plug 13 may be increased or diminished. If the opening 34 is very large, the water will enter this space at a slow rate of speed, and the quantity of

water thrown by the nozzle will be large, while the area sprayed will be small. If the opening 34 is gradually reduced, the effective length of the grooves 33 is increased, and the water flowing through these grooves is greatly accelerated and the speed of the vortex is large, consequently a fine spray will be thrown over a large area. In addition to the adjustment of the area and fineness of spray, by the up and down adjustment of the plug 13, an instantaneous and convenient adjustment is provided by the ports 43. In adjusting the opening 34 it is necessary to turn the plug 13 one or more revolutions to produce appreciable effect. The amount of water flowing through the ports 33 can, however, be regulated without changing the effective length of the grooves 33 by turning the plug 13 so that the ports 43 only partially register with the grooves 33. It is thus possible by a partial turn of the plug 13 to wholly or partially shut off the flow of water, this partial turn of the plug 13 making very little difference in the effective length of the grooves 33 and the size of the opening 34.

I claim as my invention:

1. A spray nozzle comprising a hollow supporting member adapted to carry water under pressure and having an upwardly extending branch with an opening in the top thereof, a hollow body member secured on said branch and having an outlet opening centrally located in the top thereof, a series of helical grooves being formed in the inner side of the walls of said body member, said grooves being similarly inclined, extending to a position near the top of said body member and being gradually reduced in sectional area as they ascend, and a plug threaded inside said body member and adjustable up and down therein, said plug having a cavity formed therein in open communication with the lower portion of said body member, said plug also having a top completely closing the opening through said body member and having ports formed through the walls thereof of such a size as to register with the lower portion of said helical grooves when said plug is in the open position, the walls of said plug between said ports being of such a size as to entirely shut off the flow of water through said grooves when said plug is turned to the closed position.

2. A spray nozzle comprising a hollow supporting member adapted to carry water under pressure and having an upwardly extending branch with an opening in the top thereof, a hollow body member secured on said branch and having an outlet opening centrally located in the top thereof, a series of helical grooves being formed in the inner side of the walls of said body member, said grooves being similarly inclined, extending to a position near the top of said body mem-

ber and being gradually reduced in sectional area as they ascend, a plug threaded inside said body member and adjustable up and down therein, said plug having a cavity 5 formed therein in open communication with the lower portion of said body member, said plug also having a top completely closing the opening through said body member and having ports formed through the walls 10 thereof of such a size as to register with the lower portion of said helical grooves when said plug is in the open position, the walls of said plug between said ports being of such a size as to entirely shut off the flow 15 of water through said grooves when said plug is turned to the closed position, and means by which said plug can be adjusted up and down in said body member.

3. A spray nozzle comprising a hollow 20 supporting member adapted to carry water under pressure and having an upwardly extending branch with an opening in the top thereof, a hollow body member secured on said branch and having an outlet opening 25 centrally located in the top thereof, a series of helical grooves being formed in the inner side of the walls of said body member, said grooves being similarly inclined, extending to a position near the top of said body 30 member and being gradually reduced in sectional area as they ascend, a plug threaded inside said body member and adjustable up and down therein, said plug having a cavity 35 formed therein in open communication with the lower portion of said body member, said plug also having a top completely closing the opening through said body member and having ports formed through the walls 40 thereof of such a size as to register with the lower portion of said helical grooves when said plug is in the open position, the walls of said plug between said ports being of such a size as to entirely shut off the flow of water through said grooves when said plug is turned to the closed position, and a stem 45 on said plug projecting upwardly through said outlet opening by which said plug can be turned to adjust said plug axially in said body member.

50 4. A spray nozzle comprising a hollow supporting member adapted to carry water under pressure and having an upwardly extending branch with an opening in the top thereof, a hollow body member secured on 55 said branch, a cap secured in said body member, said cap having an outlet opening centrally formed therein and being so formed and secured that it can be readily removed to give access to the interior of the nozzle, a series of helical grooves being formed in the inner side of the walls of said body member, said grooves being similarly inclined, extending to a position near the top of said body member and being gradually reduced 60 in sectional area as they ascend, and a plug 65 in sectional area as they ascend, and a plug

threaded inside said body member and adjustable up and down therein, said plug having a cavity formed therein in open communication with the lower portion of said body member, said plug also having a top completely closing the opening through said body member and having ports formed through the walls thereof of such a size as to register with the lower portion of said helical grooves when said plug is in the open position, the walls of said plug between said ports being of such a size as to entirely shut off the flow of water through said grooves when said plug is turned to the closed position. 70 75 80

5. A spray nozzle comprising a hollow supporting member adapted to carry water under pressure and having an upwardly extending branch with an opening in the top thereof, a hollow body member secured on said branch, a cap secured in said body member, said cap having an outlet opening centrally formed therein and being so formed and secured that it can be readily removed to give access to the interior of the nozzle, a series of helical grooves being formed in the inner side of the walls of said body member, said grooves being similarly inclined, extending to a position near the top of said body member and being gradually reduced 90 95 in sectional area as they ascend, a plug threaded inside said body member and adjustable up and down therein, said plug having a cavity formed therein in open communication with the lower portion of said body member, said plug also having a top completely closing the opening through said body member and having ports formed through the walls thereof of such a size as to register with the lower portion of said helical grooves when said plug is in the open position, the walls of said plug between said ports being of such a size as to entirely shut off the flow of water through said grooves when said plug is turned to the closed position. 100 105 110

6. A spray nozzle comprising a hollow supporting member adapted to carry water under pressure and having an upwardly extending branch with an opening in the top thereof, a hollow body member secured on said branch, a cap secured in said body member, said cap having an outlet opening centrally formed therein and being so formed and secured that it can be readily removed to give access to the interior of the nozzle, a series of helical grooves being formed in the inner side of the walls of said body member, said grooves being similarly inclined, extending to a position near the top of said body member and being gradually reduced 115 120 125 in sectional area as they ascend, a plug threaded inside said body member and adjustable up and down therein, said plug 130

having a cavity formed therein in open communication with the lower portion of said body member, said plug also having a top completely closing the opening through said body member and having ports formed through the walls thereof of such a size as to register with the lower portion of said helical grooves when said plug is in the open position, the walls of said plug between said 10 ports being of such a size as to entirely shut

off the flow of water through said grooves when said plug is turned to the closed position, and a stem on said plug projecting upwardly through said outlet opening by which said plug can be turned to adjust said 15 plug axially in said body member.

In testimony whereof, I have hereunto set my hand at Los Angeles, California, this 17th day of June, 1915.

ROY P. WILLIAMS.
